UNITED STATES PATENT OFFICE.

GEORGE H. MCKINLEY AND SIDNEY STEENBURGH, OF MOLINE, ILLINOIS.

SASH-WEIGHT.

932,995.

Specification of Letters Patent. Patented Aug. 31, 1909.

Application filed April 7, 1909. Serial No. 488,458.

To all whom it may concern:

Be it known that we, GEORGE H. MCKINLEY and SIDNEY STEENBURGH, citizens of the United States, residing at Moline, in the 5 county of Rock Island and State of Illinois, have invented certain new and useful Improvements in Sash-Weights, of which the following is a specification.

This invention relates to sectional sash 10 weights and other similar weights, and its object is to provide means for holding the weight-sections in alinement and for preventing relative rotation of the sections.

In the accompanying drawings Figure 1 is 15 an elevation of a sash weight embodying the features of our invention, one of the weight-sections being removed. Fig. 2 is a top plan view of a weight-section. Fig. 3 is a vertical central section through one of the 20 sections. Fig. 4 is a similar view of the bottom section.

The embodiment selected for illustration comprises a plurality of cylindrical sections 1 arranged end to end and each provided 25 with an axial opening 2 to receive the sash cord 3. The lowermost section 1^a is preferably made tapering or chamfered, as shown. The sections are supported upon any suitable means forming a shoulder upon 30 the cord 3, as, for example, a knot 4 tied in the cord.

The adjacent ends of the sections 1 and the upper end of the section 1^a are preferably formed so as to assist in holding the 35 sections alined. We have herein shown one end of each section 1 as provided with an annular rib 5, an annular groove 6 being formed in the opposite end of the section to receive the rib 5 upon an adjacent section. 40 As herein shown, the upper end of the lowermost section 1^a has a rib 5^a thereon to take into the groove 6 of the next higher section.

In order to lock the sections against rotation relatively to one another and to hold 45 the sections in alinement, we provide a key 7 which may be inserted within a slot 8 formed in one side of each section, said slot, in this instance, extending to and merging in the axial opening 2. The key 7 may be 50 of dove-tail or other suitable form in cross-section, the slot 8 being preferably shaped to conform to the key. The lowermost section 1^a is not slotted, thus providing a shoulder for the support of the key. It will be 55 seen that the key 7 prevents relative rotation of weight sections, and that said key, by reason of its dovetail form, holds said sections in alinement with one another.

The sections 1 may be placed upon the 60 cord 7 by slipping them laterally onto said cord, the slots 8 obviating the necessity of threading the sections over the end of the cord.

We claim as our invention:

1. A sectional sash weight comprising a 65 plurality of weight-sections, each having a key-receiving opening therein, a member upon which said sections are strung and supported, and a key extending longitudinally 70 of the series of sections and lying in said key-receiving openings.

2. A sectional weight comprising a plurality of weight-sections, a member upon 75 which said sections are strung and supported, said sections being slotted, and a key extending through the slots of said sections, said key being of dove-tail form in cross-section, and said slots conforming substantially to said key.

GEORGE H. MCKINLEY.
SIDNEY STEENBURGH.
